CLAIM

The ornamental design for a pie crust maker, or similar article, as shown and described.

DESCRIPTION

FIG. 1 is a perspective view of a pie crust maker, or similar article, showing my design;
 FIG. 2 is a front elevational view;
 FIG. 3 is a side elevational view;
 FIG. 4 is a top plan view;
 FIG. 5 is a rear elevational view; and
 FIG. 6 is a bottom plan view.
